The ornamental design for an exit device, as shown and described.

DESCRIPTION

FIG. 1 is an isometric view of the exit device;
 FIG. 2 is a plan view of the exit device of FIG. 1;
 FIG. 3 is a side view of the exit device of FIG. 1;
 FIG. 4 is an opposite side view of the exit device of FIG. 1;
 and,

FIG. 5 is a front side view of the exit device of FIG. 1.
 The broken lines depict portions of the article that form no part of the claimed design.
 The surface shading and/or surface lines with breaks, if any, illustrated in the figures is provided merely to highlight the contour of the design and it is not intended to be illustrative of texture or gloss.
